UNITED STATES PATENT OFFICE.

CHARLES EDWARD JOHNSON, OF CHICAGO, ILLINOIS.

PROPELLER-WHEEL.

SPECIFICATION forming part of Letters Patent No. 657,348, dated September 4, 1900.

Application filed June 26, 1899. Serial No. 721,841. (No model.)

To all whom it may concern:

Be it known that I, CHARLES EDWARD JOHNSON, a citizen of the United States of America, and a resident of the city of Chicago, county of Cook, State of Illinois, have invented certain new and useful Improvements in Propeller-Wheels, of which the following is a specification.

The object of my invention is to produce a propeller-wheel that will offer the least resistance in passing through the water and at the same time will give the greatest effective working surface to propel the vessel; and the invention consists in the novel construction set forth in the claims hereof.

Reference will be had to the accompanying drawings, in which—

Figure 1 is a side elevation of my invention. Fig. 2 is an end elevation. Fig. 3 is a top plan view. Fig. 4 is a section of one of the arms on line 4 4 of Fig. 1. Fig. 5 is a sectional detail on line 5 5 of Fig. 2. Fig. 6 is a perspective view of the leading end of the spiral blade.

In the drawings, H designates an axial shaft, and B a spiral blade located as if wound upon a large cylinder having that shaft as an axis. The spiral blade makes a little more than a complete turn about its axis and its lead is such that it presents to the water faces suitably inclined for obtaining the proper propelling effect when it is revolved.

A A A are propeller-blades rigidly uniting, respectively, the leading end, the middle, and the following end of the spiral blade to the shaft H. Each blade is set at the proper angle, has sharp edges, and at its outer end has its faces near the edges continuous with the working faces of the spiral blade. Although the blades A are set at different points along the shaft, their form and angular spacing are such that when seen as in Fig. 2 looking along the line of the shaft they appear to form an ordinary propeller having three equally-spaced blades with equal intermediate spaces. The end portions of the blade B are bent or rounded to lie approximately in

planes perpendicular to the shaft H, are narrowed by rounding the outer margins inward, and are given a thin or sharp edge, so that 50 the water is first divided, practically without displacement, by these portions and then gradually receives the thrust due to the change of the blade to a spiral direction. The outer marginal portion b³ of the rear face of the 55 body of the blade is curved forward, giving a sharp edge from end to end of this member.

The propeller is shown as provided with a tapering recess in the forward end of the shaft H to receive the correspondingly-tapered end of a power-shaft S; but instead of having this detachable connection the propeller may, if desired, be made integral with the power-shaft.

Although this propeller may be used in any 65 situation where ordinary propellers are employed, it is especially intended to be made relatively larger and to be used, partly submerged, upon boats of light draft, or to be used either partly or wholly submerged in canals, where to avoid washing the banks it is desirable to have a large surface and slow revolution.

The use of this propeller produces practically no vibration, since the ends of the spiral 75 blade strike no appreciable blow in entering the water, for they are narrow, sharp, and not inclined to the direction of movement, and the sharp-edged body of the spiral aids in dividing the water for the propeller-blades to 80 which the spiral blade is attached.

What I claim is—

1. A propeller consisting of a shaft, a spiral blade encircling the shaft but at some distance from it, and propeller-blades rigidly 85 joining the leading end, the middle, and the following end, of the spiral blade to the shaft and themselves having equal angular spacing about the shaft.

2. A propeller consisting of an axial shaft, 90 a spiral blade located as if wound upon a large cylinder having the same axis as the shaft and having its end portions approximately in planes perpendicular to said shaft, and pro-

propeller-blades rigidly joining the leading end, the middle, and the following end of the spiral blade to the shaft.

3. A propeller consisting of a shaft, a spiral blade located as if wound upon a large cylinder having the shaft as its axis and having its end portions bent into position approximately in planes perpendicular to the axis of the shaft, and propeller-blades, each having sharp edges meeting respectively the

faces of the spiral blade, integrally connecting the leading end, the middle, and the following end, respectively, to said shaft.

Signed by me at Chicago, Illinois, this 22d day of June, 1899.

CHARLES EDWARD JOHNSON.
